The ornamental design for smile creases for a container, as shown and described.

DESCRIPTION

FIG. 1 is a perspective view of the smile creases for a container;

FIG. 2 is a rear view of the smile creases for a container, the front view being a mirror image thereof;

FIG. 3 is a top view of the smile creases for a container;

FIG. 4 is a side view of the smile creases for a container; and, FIG. 5 is a broken away, cross-sectional view of a single smile crease of the smile creases for a container invention of FIG. 1 taken along line 5-5 of FIG. 3 for the purpose of clarifying its shape.

The broken line showing of structure is for illustrative purposes only, and forms no part of the claimed design.
